UNITED STATES PATENT OFFICE.

WARD T. BARKER, OF KANSAS CITY, MISSOURI.

FURNACE.

Application filed October 23, 1924. Serial No. 745,433.

This invention relates to furnaces and the primary object of the invention is to prevent super-oxygenated gases from contacting with the boiler tubes or still tubes with 5 which the furnace is associated.

Ordinarily the air which is admitted to the combustion chamber of a furnace carries an excess amount of oxygen which, not being consumed in the furnace is carried 10 over to contact with the tubes in the still or boiler, the result being that the tubes soon burn out.

In the types of furnaces and stills or boilers in which all of the products of combustion pass up the stack and all gases not generated in the furnace are admitted from atmosphere, the heat losses are considerable, due to the fact that atmospheric air must be heated to the desired temperature before it 20 acts upon the boiler.

My invention contemplates the provision of two important features which eliminate difficulties heretofore present in furnace construction. For example with my invention, 25 the amount of atmospheric or virgin air admitted to the furnace reaches the combustion chamber only in such quantities as is absolutely essential to furnish the necessary oxygen to support combustion and in view 30 of the fact that the furnace gases contacting with the boiler flues do not carry an excess of oxygen, danger of the flues becoming burnt out is eliminated. Furthermore in view of the fact that some of the flue gases 35 are fed back into the furnace with only enough atmospheric or virgin air admitted to support combustion, it will be apparent that the hot flue gases being at a relatively high temperature when they enter the combustion chamber of the furnace will require 40 very little additional heat to raise them to the temperature at which they are to contact with the flues. By this means, a considerable saving of fuel is effected and since 45 the flue gases contain a considerable proportion of carbon monoxide any oxygen remaining in the combustion chamber after combustion takes place will be neutralized so the usefulness of the still or boiler flues 50 will be prolonged since they will not be attacked by oxygen.

The construction of the preferred embodiment of my invention, whereby I may effect heat conservation and neutralization of oxy- 55 genated gases will be clearly described here-

inafter, reference being had to the accompanying drawings, in which

Fig. 1 is a perspective sectional view of a furnace and liquid vaporizer constructed in accordance with my invention.

Fig. 2 is a cross sectional view through the furnace and liquid vaporizer.

Fig. 3 is a sectional view on the line 3—3 of Fig. 2, and

Fig. 4 is a sectional view on the line 4—4 65 of Fig. 2.

The furnace 1 is constructed in the form of a hollow rectangular casing consisting of the side walls 2 and 3 and the end walls 4 and 5, the vertical walls 2, 3, 4 and 5 having 70 a top or roof 6 and a bottom or floor 7. Above the floor 7 is a transverse partition 8 supported by the vertical walls of the furnace and co-operating with the vertical transverse partition 9 and the longitudinal 75 transverse partition 10 to form two main compartments or ducts under the partition or false bottom 8. The duct 11 is L-shaped, that is it has an end space 12 which extends the width of the furnace casing 1 and it runs longitudinally from the partition 9 to the end wall 5 where it communicates with a combustion chamber or space 13 through a port 14 at one corner of the combustion chamber.

The port 14 extends the width of the duct 11 at its narrow portion and the duct 11 communicates with the combustion chamber 13 at its widest portion through a port 15 so that air from the inlet opening 16 90 may pass into the combustion chamber at both ends of the furnace. The duct, passageway or space 17 formed by the partitions 9, 10 and the side wall 3 communicates with the combustion chamber through a grid 18 formed in the wall of the transverse partition 8 and the space 17 communicates with another duct leading from the boiler flue so that gases from the boiler flue may be fed into the combustion chamber 95 by a suitable means, for example a gas impeller 19 at the end of the flue or passageway 17, see Figs. 1 and 2.

Above the air ports 14 and 15 for the combustion chamber are the burners 20 and 21. These burners may be oil or gas and they are provided with baffles 22 and 23 to direct the fuel toward the transverse center of the combustion chamber as will be well understood by those skilled in furnace con- 110

struction. The air entering the furnace below the false floor or grid so that it can be fed through the openings 14 and 15 is supplied by an air impeller in communication 5 with a preheater which utilizes the flue gases for preheating the air to raise its temperature before it enters the combustion chamber. This will be more specifically described hereinafter.

10 The products of combustion pass out through the furnace through the longitudinal series of openings 24 in the wall 2 of the furnace where they enter the liquid vaporizer 25. The particular construction 15 of the vaporizer is immaterial as it may consist of a still for cracking oil, a steam boiler or a device of like construction so it is thought it is unnecessary to specifically describe any particular liquid vaporizer, the 20 arrangement of the parallel tubes 26 being well known.

In the bottom of the liquid vaporizer is a longitudinal tunnel or flue 28 which communicates with the heat space 29 in the 25 vaporizer. The flue or tunnel 28 communicates with the casing for the gas impeller 19 by a transverse passageway 31, so that some of the gases can pass back into the combustion chamber by flowing into the flue 30 or space 17 and up through the grid 18. The major portion of the flue gases will follow this direction of travel. Some of the 35 gases however will flow through the cross flue 32 at the end of the furnace distant from the passageway 31 and into the stack 33 where they may exhaust to atmosphere. In the cross flue 32 is a casing 35 having end walls 34 and 35 which carry pipes or tubes 36 through which the flue gases pass 40 on their way to the stack. The air inlet duct or pipe 37 is connected to the casing supporting the tubes 36 so that atmospheric or virgin air may be preheated before it flows into the chamber 11 below the combustion chamber through the port or duct 45 16.

The air is admitted through the ducts 37 and 16 between which is the preheater, by an air impeller 38 at the inlet of the duct 50 37, so that air will be admitted to the furnace under forced draft, but at a very low pressure and in such volumes as to compensate for the loss of gases flowing out the stack 33. Therefore the amount of gases 55 admitted to the combustion chamber other than the gases generated by the fuel will be equal to the amount of gases passed by the impeller 19 plus the amount of air passed by the impeller 38. The only loss then, to 60 the furnace, in so far as heat is concerned will be the heat losses which pass out the stack 33 and these heat losses will be represented by the amount of flue gases passing through stack 33 to permit the necessary 65 amount of air to enter the furnace to support

combustion but in actual practice the heat losses will not be so appreciable because the fresh or virgin air fed into the furnace will first pass through the preheater and absorb some of the heat units from the exhausting 70 flue gases which pass up the stack. Consequently the heat losses will be reduced to a minimum.

Suppose the device is constructed as shown in the drawings and the fuel burners 20 and 75 21 are ignited, the air to support combustion will be admitted through the duct 37, a preheater, and duct 16 (of course the air initially will not be heated passing through the preheater). The air will be received in the 80 duct 11 and will pass into the combustion chamber through the ports 14 and 15. The products of combustion will pass over into the vaporizer 25 through the ports 24. They will pass downwardly to the duct 28, through 85 passageway 31 and back into the furnace by way of the passage 17 but since the air is continuously flowing into the furnace through the medium of the air impeller, the ducts 38 and 16, there will be a slight pressure in the combustion chamber and a slight 90 up draft in the stack 33 so some of the products of combustion will be pulled through the cross duct 32 passing through the pipes and the preheater and then pass 95 out through the stack.

The volume of the products of combustion which pass out through the stack will be equal to the amount of air introduced into the furnace to support combustion and theoretically only so much air will be fed into the furnace as is necessary to support combustion, it being one of the purposes of this invention to eliminate any oxygen from the vaporizer but practically this cannot be fully 100 accomplished, however the amount of oxygen laden air which is not consumed by the flames will be a very small percentage of the gaseous fluid passing around the tubes of the vaporizer and such a small amount of 105 oxygen will not attack the tubes because it will be so thoroughly diluted by the carbon monoxide gases as to render it impotent as an attacking medium.

Since the major portion of the hot gases 110 cooled only by the absorption of the heat units or tubes in the vaporizer will be fed back into the combustion chamber, it will be apparent that they will need have their temperature raised only to make up the difference between their present temperature and their required temperature. For example if the used flue gases re-enter the combustion chamber at 1000° F. and it is desired that they be passed over to the vaporizer at 1400° F., it will be necessary only to supply sufficient heat to raise the flue gases 400° F., with enough heat to raise the preheated air, if any additional heat is required, to 1400° F. 115 This results in a great saving over a con- 120 125 130

struction of furnace in which all the gases must be heated from atmospheric temperature to the desired temperature, so there are two important features of my invention in 5 a generic sense, one the conservation of heat and the other the elimination of detrimental oxygenated fluids which will attack the tubes of the vaporizer, both features resulting in a marked saving in the operation of furnaces 10 and while I have specifically described in detail what appears to me to be the very best form of my invention, I wish it to be understood that I do not limit myself to the exact construction shown but reserve the right to 15 make such changes in form, proportion and minor details of construction as properly come within the scope of the appended claims.

What I claim and desire to secure by Letters-Patent is:—

1. The combination with a furnace and a liquid vaporizer in which heated gases pass from the furnace to the vaporizer, of an atmospheric air-receiving chamber in the 25 furnace below the combustion chamber thereof, the air chamber communicating with the combustion chamber at its respective ends, a passageway for heated gases below the combustion chamber having ports in the top 30 thereof whereby heated gases from the passageway may pass into the combustion chamber intermediate the ends of the combustion chamber, a conduit for exhausting some of the heated gases from the vaporizer to atmosphere, a conduit for leading some of the 35 heated gases from the vaporizer to the passageway, and means for introducing atmospheric air to the atmospheric air receiving chamber.
- 40 2. The combination with a furnace and a liquid vaporizer in which heated gases pass from the furnace to the vaporizer, of an atmospheric air receiving chamber in the furnace below the combustion chamber thereof, the atmospheric air receiving chamber communicating with the combustion chamber at its respective ends, a passageway for heated gases below the combustion chamber having ports in the top thereof whereby heated air from the passageway may pass into the combustion chamber intermediate the ends of the combustion chamber, a conduit for exhausting some of the heated gases from the vaporizer to atmosphere, a conduit for leading some of the heated gases from the vaporizer to the passageway, and means for introducing atmospheric air to the air receiving chamber, the amount of atmospheric air admitted to the first named air chamber 50 being substantially equal to the amount of hot gases exhausted from the vaporizer.
- 45 3. The combination with a furnace and a liquid vaporizer in which heated gases pass from the furnace direct to the vaporizer, of an atmospheric air receiving chamber com-
- 55 municating with the combustion chamber at its respective ends, a passageway below the combustion chamber having ports in the top thereof whereby heated gases from the passageway may pass into the combustion chamber intermediate the ends of the combustion chamber, a conduit for exhausting some of the heated gases from the vaporizer to atmosphere, a conduit for leading some of the heated gases from the vaporizer to the passageway, means for introducing atmospheric air to the air receiving chamber and a pre-heater in the conduit leading from the vaporizer to atmosphere through which the atmospheric air for the first named air chamber passes.
- 60 4. The combination with a furnace and a liquid vaporizer in which heated gases pass from the furnace to the vaporizer, of an air chamber in the furnace below the combustion chamber thereof, the air chamber communicating with the combustion chamber at its respective ends, a passageway below the combustion chamber having ports in the top thereof whereby hot gasses from the passageway may pass into the combustion chamber intermediate the ends of the combustion chamber, a conduit for exhausting some of the heated gases from the vaporizer to atmosphere, a conduit for leading some of the heated gases from the vaporizer to the passageway, means for introducing atmospheric air to the air receiving chamber, and an impeller in the conduit which connects the vaporizer with the hot air chamber.
- 65 5. The combination with a furnace and a liquid vaporizer in which heated gases pass from the furnace to the vaporizer, of an air chamber in the furnace below the combustion chamber thereof, the air chamber communicating with the combustion chamber at its respective ends, a passageway below the combustion chamber having ports in the top thereof whereby hot gases from the passageway may pass into the combustion chamber intermediate the ends of the combustion chamber, a conduit for exhausting some of the heated gases from the vaporizer to atmosphere, a conduit for leading some of the heated gases from the vaporizer to the passageway, means for introducing atmospheric air to the air receiving chamber, and an impeller in the means for admitting atmospheric air to the first named air chamber.
- 70 6. Apparatus of the character described including separate furnace and vaporizer chambers in communication for passage of gases from the furnace chamber to the vaporizer chamber, means in the furnace chamber defining a zone of primary combustion, a floor forming a false bottom in the furnace chamber, and means partitioning the space beneath the floor to define a recirculation gas chamber and a separate air chamber, the floor having openings providing for passage

of air from the air chamber to said zone of primary combustion and for passage of gases from the gas chamber to the furnace chamber exteriorly of said zone, means for 5 conducting gases from the vaporizer chamber to said gas chamber for recirculation, and means for delivering fresh air to the air chamber for supporting primary combustion.

7. Apparatus of the character described 10 including separate furnace and vaporizer chambers in communication for passage of gases from the furnace chamber to the vaporizer chamber, a horizontal partition forming a false bottom in the furnace chamber, means partitioning the space beneath said bottom to form a gas chamber and a separate air chamber at the end of the gas chamber, means in the furnace chamber defining a zone of primary combustion over 15 the air chamber, means for conducting gases from the vaporizer chamber to the gas chamber for recirculation, and means for delivering fresh air to said defined zone for supporting combustion, said horizontal partition having openings for passage of fresh air from the air chamber to the zone of primary combustion and from the gas chamber to the furnace chamber externally of said zone.

30 8. Apparatus of the character described including furnace and vaporizer chambers in communication for passage of gases from the furnace chamber to the vaporizer chamber, the furnace chamber including primary 35 combustion chambers at its respective ends, a passageway for heated gases below the furnace chamber and opening through the floor thereof between the primary combustion chambers, a stack, a conduit for conducting gases from the vaporizer chamber to the stack, and means for returning some 40 of said gases to said passageway for recirculation.

45 9. Apparatus of the character described including furnace and vaporizer chambers in communication for passage of gases from the furnace chamber to the vaporizer chamber, the furnace chamber including primary combustion chambers at its respective ends,

a passageway for heated gases below the 50 furnace chamber and opening through the floor thereof between the primary combustion chambers, a stack, a conduit for conducting gases from the vaporizer chamber to the stack, and means for diverting some 55 of the gases from said conduit to said passageway for recirculation.

10. Apparatus of the character described 60 including furnace and vaporizer chambers in communication for passage of gases from the furnace chamber to the vaporizer chamber, horizontal baffles at the ends of the furnace chamber forming primary combustion chambers, burners in said combustion chambers, means for delivering atmospheric air 65 to said combustion chambers, a floor for said furnace chamber having a port opening to the furnace chamber between the combustion chambers, a passageway leading from the vaporizer chamber beneath said floor and 70 adapted for delivering gases from the vaporizer chamber through the floor of the furnace chamber for recirculation, a stack, and means connecting said passageway with the stack.

75 11. Apparatus of the character described 80 including furnace and vaporizer chambers in communication for passage of gases from the furnace chamber to the vaporizer chamber, horizontal baffles at the ends of the furnace chamber forming primary combustion chambers, burners in said combustion chambers, means for delivering atmospheric air to said combustion chambers, a floor for 85 said furnace chamber having a port opening to the furnace chamber between the combustion chambers, a passageway leading from the vaporizer chamber beneath said floor and adapted for delivering gases from the vaporizer chamber through the floor of the furnace chamber for recirculation, a stack, and means connecting said passageway with the stack, and means for regulating 90 proportional flow of said gases to the passageway and stack.

In testimony whereof I affix my signature.

WARD T. BARKER
